(57) **CLAIM**

The ornamental design for a tent stove as shown and described.

DESCRIPTION

FIG. 1 is a front, top, and left perspective view of a tent stove showing my new design;

FIG. 2 is a rear, bottom, and left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, rear, and right perspective view, showing the tent stove in a storage state.

The broken lines in the drawings depict portions of the tent stove that form no part of the claimed design. Shadows and reflections do not represent any particular color, material, texture or finish.

1 Claim, 9 Drawing Sheets
